UNITED STATES PATENT OFFICE.

MOSES MICHAELIS, OF NEW YORK, N. Y.

DESIGN FOR A CANDY-BOX.

SPECIFICATION forming part of Design No. 32,212, dated February 13, 1900.

Application filed January 16, 1900. Serial No. 1,699. Term of patent 3½ years.

To all whom it may concern:

Be it known that I, MOSES MICHAELIS, a citizen of the United States, residing at New York, in the borough of Manhattan and State of New York, have invented and produced a new and original Design for Candy-Boxes, of which the following is a specification, reference being had to the accompanying drawings, forming part thereof, and in which—

10 Figure 1 is a side elevation of the box, and Fig. 2 a plan.

As shown in the drawings, the leading or material feature of my design consists of a pillar-shaped box which comprises a pedestal 15 of rectangular shape constructed with a large stepped inferior base - piece and a smaller stepped superior base-piece, between which base-pieces the rectangular main body of the pedestal is disposed, a cylindrical shaft, a capital formed with a basal bead, a curved flaring portion and a frusto-pyramidal top, and a spherical knob on top of the capital.

In the drawings, A indicates the rectangular pedestal, provided with a large inferior base-piece A', which is stepped as shown at 25 a, and with a smaller superior base-piece A², which is stepped as shown at a'.

B indicates a cylindrical shaft.

D indicates a capital which is provided with a bead d, surrounding its lower part, curved 30 outwardly-flaring sides d', and a frusto-pyramidal portion or top d², from which extends a spherical knob E.

What I claim is—

The design for a candy-box, as described 35 and substantially as shown.

In testimony that I claim the foregoing as my invention I have signed my name in presence of two subscribing witnesses.

MOSES MICHAELIS.
